GARMENT-PACKAGE BOARD

Leonard J. Bezark, Chicago, Ill.

Application July 31, 1939, Serial No. 287,436

10 Claims. (Cl. 223—71)

The present invention relates generally to packaged garments and devices for such. In particular it relates to a stiffening core board for folded garments, as for example, for the display of shirts for sale. In such specific use the device is known as a "shirt board," but its utility is not limited to shirts, nor to display of garments for sale.

It is a common practice to display garments for sale in a neatly folded pack, which may be generally rectangular or square, with the face or upper front of the garment exposed on the face of the pack. This necessitates folding the remainder of the garment into the pack or onto the underside of the pack. To keep the parts so folded in place, thus to preserve the neat appearance of the pack, pins or stickers are employed, or envelopes are used. Sometimes stiffening cardboard sheets or forms are used within the pack, or within portions of the pack, such as in collars.

Purchasers often call for opening the pack to inspect the style, structure or material of the garment. This calls for removing pins or stickers, opening the folds, and then re-making the pack. This leaves old pin-holes or sticker-spots, and makes new ones. It is time consuming and it injures the appearance of the garment for a sale or for a second opening of the pack. Also, in the factory, or in a laundry, a garment is ironed and a pack made at the same time, the ironer stopping to insert pins or place stickers.

According to the present invention, a package is provided which may be easily formed, opened and remade without pins or stickers, and which is a firm package of neat appearance for display of shirts, dresses, suits of underwear, pajama suits, uniforms for nurses, waitresses, etc.

It is an object of the invention to provide a neat appearing reinforced pack of a garment or combination of garments.

A particular object of the invention is to provide a stiffening core which lies generally inside the pack, and which permits of a closing or tieing band about the pack to hold the pack together.

A further object of the invention is to provide a single core board having a movable tongue therein which carries a band to tie around the finished pack.

Other and ancillary objects and advantages of the invention will be apparent from the following description and explanation of the invention as shown in the accompanying drawing in which:

Fig. 1 represents a board suitable for shirts and the like, the board being shown in open flat form.

Figs. 2 and 3 are modified "tail" ends of such a board.

Fig. 4 is a modified collar-end of such a board.

Fig. 5 is a modified board more particularly useful for short garments.

Fig. 6 is a front view of a shirt-pack according to the present invention.

Fig. 7 is a rear view of the pack of Fig. 6.

Fig. 8 is a view showing a shirt partly wrapped about a shirt board.

It is to be understood that the drawing is merely exemplary, and that it does not limit the invention or the use thereof.

The invention is illustrated by reference to its use for men's shirts, from which it will be obvious how the invention may be varied or used for other types of garments.

In displaying men's shirts the front is on the face of the pack. Collars vary, but these variations are seen without opening the pack. It is an important part of the display to present the collars. There are collar-band shirts, and collar-attached shirts to which the invention may be accommodated, in one or more ways, as will be explained.

Referring to Fig. 1, there is shown a shirt-board used in the pack appearing in Fig. 6 for an attached collar shirt. The board has a main body portion 9 which is substantially the size of the resulting pack, having in particular the pack-bottom-end 10, and the collar-end 11. The line 10 is important in providing for folding the excess length of the garment over onto the back face, where it may be covered by a tongue 12 struck from the body of the board 9. The excess garment and the location of the tongue 12 are such as to permit a neat inclusion of the excess garment between the tongue 12 and the body 9. Further to assure neatness, the body 9 may be extended by an additional part 13 from the line 10, which thus becomes a folding line. The extension 13 has an edge 14 parallel to line 10, over which edge the excess garment may be folded. The dimensions are such that the folding line 10 breaks the integral unit into a long section 9 and a short section 13. The wrapping of the garment about the core is such as to maintain this relationship.

Tongue 12 is so placed in body 9 that it is adapted in one of its possible positions to lie over the short section. In Fig. 1 the structure is such as to accomplish this with the tongue extending in the direction of its original formation. Tongue 12 is tapered for neatness in appearance, and also to permit placing its hinging line 15 high in the

collar end 11 of body 9. Its wide bottom edge 16 permits a good spread in holding down the short section, which is of importance where the extension 13 is absent.

The tongue has another important function. Its function to hold down the short section depends upon holding down the tongue in the finished pack. This may be done by a loose band encircling the pack over the tongue, but preferably, the tongue is used to carry a band or tie means 17 in one or two lengths. This may be secured fixedly to the tongue by staples, glue, stickers or other means. Preferably the tie 17 is a single strip of cord, ribbon or tape which slides lengthwise of itself in the tongue. The tongue 12 may have one or more simple slits to permit this, but preferably it is cut with tongue 18 cooperating with two slits 19 as shown. This permits inserting a flat tie 17 by bending the tongue 12 to present its little tongue 18. Advertising may be used on flat tying tape.

The collar end 11 may be varied according to the garment. As shown in Fig. 1 the strip 20 is foldable on perforated scored line 21, and fits into a soft collar to permit it to be presented in up-standing relation to the body of the reinforcing board 9 as shown in Fig. 6.

In Fig. 6 the shirt S has attached-collar C. The tie 17 is shown. It is particularly to be noted that the exposed portions 23 are but slightly extended beyond the main width of the shirt face. This is accomplished intentionally by providing the extension 13 (Fig. 1) with flaring sides 24, in order to make the shorter or under-section relatively wider than the longer or face-section in the vicinity where the tie 17 goes around the pack. Thus the force of the tie is exerted on the under-section and no wrinkles and pulling are caused on the face of the shirt S. The taper also has other functions. In the folded package, it keeps the tie 17 from slipping toward the collar, which it may do to some extent within the holding structure 18-19 specifically described. Any looseness in the band tends to let the band slip toward the collar end, and the tongue 12 to rise accordingly. The result of the flaring end is to counter-balance these tendencies, and to provide and maintain a tight package.

Still another function of the sides 24, is dependent on the fact that these lines are non-parallel. Folding a garment over these edges, binds it against easy slipping in both directions. With the edge of a garment folded over edge 14, and the sides folded over sides 24, there is no direction in which the garment may slide relative to the board. The flaring extension 13 therefore provides means for holding the garment in non-sliding relation to the board.

The formation of flaring side edges 24 calls for a certain waste of stock in manufacture, which may be avoided by other modified forms. Thus, for example, in Figs. 2 and 3 holding tongues are shown in the modified extensions illustrated. However, these may be used with tapered or flaring sides. In Fig. 2, extension 25 may have parallel side edges 26, coextensive with the body portion 10 (not shown). It has edge 27 over which the tail of the garment may be folded. But it also has a tongue 28 extending to said edge, under which the tail of the garment may be tucked to hold it to the board. Fig. 3 has an extension 29 similar to that of Fig. 2, but shows a tongue 30 above edge 31, for use where the garment tail may be longer, and 75

hence come up higher on the extension when folded over.

Fig. 4 represents a modified collar end having the projecting portion comprising the three tongues 33, 34 and 35 and the forming cuts 36, 37, 38 and 39. This structure will serve for an attached-collar to hold it flat, by inserting the outer two tongues or the center tongue under the collar. It will serve a collar-band shirt by 10 inserting tongue 34 into the space for the back-stud. It is readily seen that with the collar-portion well hooked at one end of the board, and with the tail end folded over line 10, or preferably over edge 14, then line 10, the front 13 of shirt S will be neatly displayed. By untying the tie 17 the shirt may be removed and put back without any difficulty or damage to the pack.

Further modifications are shown in Fig. 5 20 on which a short garment such as a polo shirt may be displayed. This has a body portion 41 over the edge 42 of which the tail may be folded. The top has a collar holding strip 43. A modified form of tongue is shown in which tongue 44 is struck out and adapted to be turned through 180° to hold the tail portions. Tie 45 is secured to the tongue. This structure may be used where it is desirable to show the back of the garment, without opening the pack. The hole from which 30 the tongue is taken leaves a window for this purpose.

In operation the device may be used as follows. The shirt S is placed face down. The device as shown, or one of its modifications, is 33 placed on the back of the shirt (see Fig. 8). The collar portion is placed within the collar C. The tail T of the shirt is folded over the bottom edge, and where a tongue 30 is provided (as in Fig. 3) the tail is placed under it. Fig. 9 40 shows the shirt so placed with the right side folded in over the tail, the sleeve s being shown largely above the folding line 10, and the tie-tongue 12 being opened out to be free of the sleeves. Then the left side of the shirt is similarly 45 folded over from the unfolded position of Fig. 8. Following this, the whole is folded on score line 10, and the tongue 12 is tied down as shown in Fig. 6.

In the preferred form the tongue is so cut 50 and located that it is not necessary to produce a severe fold at its hinging line. Thus, the package of Fig. 7 may be made by slipping the parts under the tongue. The board of Fig. 5 may be used with a short section lying above the indicated hinging line of tongue 49 by folding the tongue itself without using the indicated folding line. Likewise, the tongue 12 of Fig. 1 may be folded through 180°, whereby it will extend from the top. From this position it may be used to include a length as long or longer than the length of core section 9. Therefore, it will be understood that the preferred structures and limitations appearing in some claims are not limitations of the invention.

It will thus be seen how the device may be altered, and how it may be used variously. For two-piece outfits, such as pajamas, one piece may be included wherever desired, without in any way disturbing the display of the other piece, or the advantages of the device.

The invention comprehends both the pack and the board, with such modifications as may fall within the scope of the appended claims.

Fig. 2 also shows a structure in which the tongue-carrying portion 9 and the extension por-

tion 25 are separate sheets of material, which may be used separately, but which are shown united together by a strip of adhesive tape 25a.

I claim:

1. A packaged garment comprising a garment folded upon itself to provide two superimposed sections and a fold joining them, a stiffening core board coincidentally folded in two portions with free ends and located within the outer confines of said sections, said portions extending from their fold toward the other ends of said sections, one of said portions having its free end provided as a collar-support and being associated with the collar end of the garment, a tongue struck from said core board within the said collar end and positioned and adapted to include one of said sections and portions between the tongue and the body of the core board, and means providing a band holding down said tongue and encircling the garment.

2. A packaged garment comprising an elongated core board folded to provide superimposed short and long lengths with free ends and a fold between them, the free end of the long length being provided as a collar-support, a tongue struck from the long length and hinged thereto in a location to permit including the short length between the tongue and the long length, a garment wrapped about said core before folding and included with the short length between said tongue and said long length, the collar-support being associated with the collar-end of the garment, and a band holding down said tongue and encircling the garment.

3. A packaged garment comprising a garment with a two-ply collar portion and a front folded backwardly on itself to provide a long front section with collar at the top and a fold at the bottom and a short section of garment on the underside, a stiffening core board located between said long and short garment sections in a long and a short section from a coincident fold, the long section at its free end being provided with a portion entering the inter-ply space of said collar portion, a tongue struck from said long section of the core board, said tongue being positioned and adapted to include said short section between the tongue and the body of the core board, and a band holding down said tongue and encircling the garment.

4. A packaged garment comprising an elongated core board folded to provide superimposed short and long lengths with free ends and a fold between them, a tongue struck from the long length in a location to permit including the short length between the tongue and the body of the long length, a collar-fitting portion on the free end of the long length, a garment with collar portion wrapped about said core board before folding with the collar-fitting portion of the board fitting with the collar portion of the garment, said tongue including the garment with the short length of board between the tongue and the long length of board, and means for holding down said tongue to the garment.

5. A garment-package board comprising a sheet of board over which a garment may be wrapped, said sheet being weakened to permit a fold in said board to provide superimposed long and short lengths with free ends, a tongue struck from the body of the long length over an area in part covered by the short length in folded position and hinged to the long length to include

the short length between the tongue and the long length, and means on the short length adapted to bind a garment wrapped thereon and folded with the board.

6. A garment-package board comprising a sheet of board over which a garment may be wrapped, said sheet being weakened to permit a fold in said board to provide superimposed long and short lengths with free ends, a tongue struck from the body of the long length over an area in part covered by the short length in folded position and hinged to the long length to include the short length between the tongue and the long length, and a tongue struck from within the area of the short length to receive under it a portion of a garment folded over the edge end of the short length.

7. A garment-package board comprising a sheet of board over which a garment may be wrapped, said sheet being weakened to provide a fold in said board to provide superimposed long and short lengths with free ends, a tongue struck from the body of the long length over an area in part covered by the short length in folded position and hinged to the long length to include the short length between the tongue and the long length, and a collar fitting portion at the free end of the long length.

8. A garment-package board comprising a sheet of board over which a garment may be wrapped, said sheet being weakened on a single line to permit a fold in said board to provide superimposed long and short lengths with free ends, a tongue struck from the body of the long length over an area in part covered by the short length in folded position and hinged to the long length to include the short length between the tongue and the long length, and a collar fitting portion constituting the free end of the long length, the short length as a lineal extension of the long length having means adapted to bind a garment wrapped thereon and folded with the board.

9. A garment-package board comprising a sheet of board over which a garment may be wrapped, said sheet being weakened to provide a fold in said board to provide superimposed long and short lengths, a tongue struck from the body of the long length over an area in part covered by the short length and hinged to the long length to include the short length between the tongue and the long length, a collar fitting portion at the end of the long length, and the short length being slightly tapered in one direction to aid in holding a garment wrapped thereon against slipping on the board.

10. A garment-package board comprising a substantially rectangular elongated board provided at a free end with fitting means for a collar of a garment, said board being provided with a tongue struck from the board near the said collar end and projecting hingingly towards the other end, said board being scored for folding to bring said other end beneath said tongue, whereby a garment wrapped on said board before folding may lie under the tongue, and the tongue may provide a location for an encircling band which holds the tongue in its holding position, the portion of the board held by the tongue being wider than the portion providing the tongue at the location of said encircling band.
